Chittenden & Mead,

Making Hoops,

No 10,563,

Patented Feb. 28, 1854.

UNITED STATES PATENT OFFICE.

JOHN W. CHITTENDEN AND WILLIAM C. MEAD, OF VEVAY, INDIANA.

MACHINE FOR SPLITTING HOOPS.

Specification of Letters Patent No. 10,563, dated February 28, 1854.

To all whom it may concern:

Be it known that we, JOHN W. CHITTENDEN and WM. C. MEAD, both of Vevay, Switzerland county, Indiana, have invented 5 a new and useful Machine for Splitting Hoops; and we do hereby declare the following to be a full, clear, and exact description thereof, reference being had to certain drawings.

10 The object of our invention is to provide a machine for racking or riving hoops, better and far more expeditiously than is now done, in any manner known.

In the supposed drawings Figure 1 is a 15 side elevation and Fig. 2 is a plan of our machine.

(a) is a suitable framework.

(b) is a tab wheel operating a trip-hammer (c) by means of the tabs (d). It 20 also by means of pulleys (e f f') and bands (g) actuates a pair of horizontal feed rollers (h i). Of these the upper roller (h) is hung in a sliding frame or gate (k), to the top of which a cord being attached 25 and carried over a sheave (l) to a treadle (m) the pressure of the foot on the treadle raises the uppermost roller, when it is wanted out of the way, and another treadle (n) applied to the foot of the gate (k), 30 gives facility for lowering the said roller and for inclosing its pressure by stress upon the treadle.

(o, p) are two vertical rollers, shown by dotted lines immediately in front of the 35 feed rollers. Of these, the roller (o) is hung in a gate (q), capable of being drawn away from the other roller by the spring lever (r), by means of which, also the roller can be pushed in again, till the lever, catching over the notch (s) is permanently secured to the inner position, and the lever itself being made broad and thin, serves as a 40 spring to hold the roller to the stuff. The object of the vertical rollers, is to assist the feed rollers in holding the bolt or pole square to the work, without canting or wabbling, and the object of the appliances for the temporary withdrawal of the rollers, is to allow the bolt being turned occasionally, 45 with either side up, according to the observed tendency of the grain to run out to one side or the other.

(t) is another horizontal roller placed a little in front of the vertical ones, and 50 about on a level with the lower feed roller. This serves as an anvil which supports the

portion of the bolt which receives the blows of the hammer.

(u) is another horizontal roller in a vertically sliding frame through the lower 60 part of which, passes the same treadle (n) which is connected to the gate (k), so that when the upper feed roller is lifted, the roller (u) is also lifted, but at other times (u) serves the purpose of holding down 65 the end of the bolt in the bent position which with the blows of the hammer serves to separate the individual strips from each other.

The standard (v) of the hammer, is capable of a slight adjustment toward and from the tab wheel so as to increase or diminish the range of the hammer, and by consequence the force of the blows, according to the size and nature of the stuff. 70

-(w) is a break pin which being by means of its handle (H), pushed under the tail of the hammer stock, suspends for the time its operation.

The explanation of the process should 80 perhaps be premised with the remark that it is very well known to hoop and stave makers, that in the operation of riving timber with the frow or cleaving knife the cleavage has a slight tendency to run out 85 toward the side away from which the piece is being bent, and this obliges the frequent turning over of the stuff in order to counteract the irregularity by one of an opposite tendency. Several of the provisions of our 90 machine have reference to this fact.

The operation is as follows: The bolt being got out to the right size, and checked at the end just as it is designed to split, the checked end is inserted between the feed 95 rollers, and the upper one being brought down hard upon it, it is thereby fed in between the vertical gripping rollers which by the action of the spring lever permits its entry, and at the same time keeps a firm 100 grasp upon it. As soon as the advancing end reaches the anvil roller (t) the hammer is liberated, and successive beating upon the bolt, continues the checks farther and farther into the wood. As soon as the stick 105 gets far enough advanced, the foremost end is depressed so as to pass under the roller (u) which holding down to the bent position indicated by the red lines, gives it a tendency to start or separate at the growths, 110 which the checks already made, and the blows of the hammer complete, by dividing

the bolt into as many uniform strips as there are checks in the end of the bolt. It should be stated however that many pieces have the grain running so much to one side, that by a judicious presentation of the stick it may be put right through without turning, the racking tendency and that of the grain exactly counteracting each other. The usual process of riving timber is a severe and laborious task, so that this is truly a labor-saving machine.

Any good clear rifted hickory, oak, cypress, swamp-ash or other tough clear-grained wood are suitable for the purpose, and from its entire manageability, much wood, other-wise impracticable is made available.

We claim herein, and desire to secure by Letters Patent,

The feed rollers, the gripping, anvil and bending rollers, or their equivalents arranged and constructed substantially as described in combination with a trip hammer as described, for the purpose of racking or splitting apart timber (previously checked as herein explained) for hoops.

JOHN W. CHITTENDEN.
W. C. MEAD.
